UNITED STATES PATENT OFFICE.

RUDOLF GOLDSCHMIDT, OF BERLIN, GERMANY, ASSIGNOR TO DET TEKNISKE FORSØGSAKTIIESELSKAB, OF ORDRUP, CHARLOTTENLUND, DENMARK, A COMPANY OF DENMARK.

MECHANISM FOR CONVERTING ROTARY INTO RECIPROCATORY MOTION.

1,415,335.

Specification of Letters Patent.

Patented May 9, 1922.

Application filed January 29, 1921. Serial No. 441,097.

To all whom it may concern:

Be it known that I, RUDOLF GOLDSCHMIDT, a citizen of Germany, and a resident of Berlin, Germany, have invented certain new 5 and useful Improvements in Mechanism for Converting Rotary into Reciprocatory Motion, of which the following is a specification.

This invention relates to mechanism for converting rotary into reciprocatory motion 10 wherein a reciprocatory member is reciprocated by a centrifugal weight or weights pivoted to the member.

One of the objects of the present invention is to overcome the necessity of employing 15 heavy centrifugal weights rotating at great radius.

According to the present invention the arm carrying the centrifugal weight is jointed so that the outer part of the arm carrying 20 the weight is capable of angular movement in relation to the inner part of the arm.

In order that the invention may be more clearly understood reference is hereinafter made to the accompanying drawings where- 25 on:

Fig. 1 is a side view of one form of the improved mechanism.

Fig. 2 is a plan view thereof.

Fig. 3 is a view corresponding to Fig. 1 30 illustrating a modified form of mechanism after the main shaft has been rotated through ninety degrees.

The invention is illustrated on the drawings as applied to the reciprocation of a 35 member 1 movable between guides 2 in a horizontal path.

Rotatably journaled in the member 1 is a cross shaft 3 to which are fixed one or more arms 4 rotatably supporting on their outer 40 ends a pin or shaft 5 upon which is mounted an arm 6 carrying a weight 7. The arm 6 is rotated either through gearing (not shown) or directly from a chain wheel 8 around which is trained a chain 9 which also passes 45 over a chain wheel 10 mounted on the member 1. It will be seen that the arm 4 rotates about the axis of the cross shaft 3 as its centre and that the arm 4 is jointed to the arm 6 which may be adapted to rotate about 50 the axis of the pin or shaft 5 as its centre. It will be understood that instead of chain wheel mechanism 8, 9 and 10, the chain gear-

ing may be replaced by any other suitable form of driving mechanism and that the chain wheel 8 may be adapted to drive the 55 arm 6 at any desired angular velocity through gearing (not shown). The relative positions of the arms 4 and 6 during rotation of the arm 4 will depend upon the angular velocity of the arm 4 about its centre 3 relative to 60 the angular velocity of the arm 6 about its centre 5. The centrifugal action of the weight 7 will vary according to the variation in the relative positions of the two arms. For example, if the arm 6 were 65 driven by the chain wheel 8 by gearing (not shown) so that the arm 6 made two revolutions about its centre 5 for each revolution of the arm 4 about its centre 3, then when the arm 4 had rotated through 90° from the 70 position shown in Fig. 1, the parts would occupy the position shown in Fig. 3 where the centrifugal action of the weight 7 is smaller than the centrifugal force of the weight 7 in the position shown in Fig. 1. 75 In the position illustrated in Fig. 1, however, the centrifugal action of the weight 7 is greater than if it were fixed to an undivided arm of a length equal to the distance between the centres of the cross shaft 80 3 and weight 7, this being due to the additional angular velocity of the arm 6.

It will be understood that the motion of the weights 7 may be readily varied by mounting the chain wheels 10 so as to be 85 capable of rotation on the cross shaft 3 and rotating the chain wheels 10 by any suitable mechanism.

The cross shaft 3 may be rotated in any 90 convenient manner as for example by flexible shafting from a prime mover.

The gyrations of the centrifugal weight or weights 7 will effect reciprocation of the member 1 within the guides 2 and in order to obtain a balancing effect in the system, 95 the member 1 may be fitted with any desired number of rotatably mounted arms 4 and 6 and weights 7, but for the sake of clearness only two such rotatable arms and weights have been illustrated on the drawing.

The foregoing mechanism is applicable 100 to any form of reciprocatory member such as that shown on the drawings and is particularly applicable to reciprocatory mem-

bers such as those described in the specification accompanying my co-pending patent applications Serial Nos. 436,206, filed 10th Jan. 1921, 436513 filed 11th Jan. 1921 and 5 441099 filed 29th Jan. 1921.

Claims.

1. Mechanism for converting rotary into reciprocatory motion comprising a reciprocatory member, a jointed arm pivoted to 10 said member and a weight mounted on the outer part of said jointed arm.

2. Mechanism for converting rotary into reciprocatory motion, comprising a reciprocatory member, an arm pivotally mounted 15 thereon, means for rotating said arm and a centrifugal weight jointed to said arm and capable of angular movement in relation thereto.

3. Mechanism for converting rotary into 20 reciprocatory motion comprising a reciprocatory member, a rotary arm pivotally mounted on said member, an outer arm pivotally mounted at the free end of said arm, a weight carried by said outer arm, means 25 for rotating said rotary arm and means for rotating said outer arm.

4. Mechanism for converting rotary into reciprocatory motion, comprising a reciprocatory member, horizontal guides for said 30 member, a driven shaft journaled in said member, an inner arm fixed at one end to said shaft, an outer arm journaled at the free end of said inner arm, a weight mounted

on said outer arm and means for rotating said outer arm.

5. Mechanism for converting rotary into reciprocatory motion, comprising a reciprocatory member, an inner arm pivotally mounted at one end on said reciprocatory member, gearing carried by the free end of 40 said inner arm adapted for actuation from said reciprocatory member during angular movement of said inner arm and an outer weighted arm rotatably driven from said gearing.

6. Mechanism for converting rotary into reciprocatory motion, comprising a reciprocatory member, horizontal guides for said member, a driven shaft journaled in said member, an inner arm fixed at one end to 50 said shaft, an outer arm journaled at the free end of said inner arm, a weight mounted on said outer arm, a gear wheel mounted at the free end of said inner arm and rotatable with said outer arm and transmission 55 gearing from said reciprocatory member to said gear wheel.

7. Mechanism for converting rotary into reciprocatory motion, comprising a reciprocatory member, a plurality of jointed arms 60 pivotally mounted on said reciprocatory member and a weight mounted on the outer part of each of said jointed arms.

In testimony whereof I hereunto affix my signature.

RUDOLF GOLDSCHMIDT.
